CLAIM

We claim the ornamental design for a portable angle impact tool, as shown and described.

DESCRIPTION

FIG. 1 is a left side view of a portable angle impact tool according to the new design.

FIG. 2 is a right side view of the portable angle impact tool shown in FIG. 1.

FIG. 3 is a front view of the portable angle impact tool shown in FIG. 1.

FIG. 4 is a rear view of the portable angle impact tool shown in FIG. 1.

FIG. 5 is a top view of the portable angle impact tool shown in FIG. 1.

FIG. 6 is a bottom view of the portable angle impact tool shown in FIG. 1; and,

FIG. 7 is a perspective view of the portable angle impact tool shown in FIG. 1.
